ATTORNEY

UNITED STATES PATENT OFFICE

118,171

DESIGN FOR A PRINTING TYPE FONT

Imre Reiner, Lugano, Switzerland

Application September 15, 1939, Serial No. 87,243

Term of patent 7 years

To all whom it may concern:

Be it known that I, Imre Reiner, a citizen of Hungary, residing at Lugano, Switzerland, have invented a new, original, and ornamental Design for Printing Type Font, of which the following is a specification, reference being had to the accompanying drawing, forming part thereof.

The figure of the drawing is a face view of the printing type font showing my design.

I claim:

The ornamental design for a printing type font, as shown.

IMRE REINER.
